UNITED STATES PATENT OFFICE.

ANTON PRIER, CHARLES DOHERTY, AND PIERCE E. EVERETT, OF KANSAS CITY, MISSOURI.

SELF-CLOSING FAUCET.

SPECIFICATION forming part of Letters Patent No. 278,597, dated May 29, 1883.

Application filed December 9, 1882. (No model.)

To all whom it may concern:

Be it known that we, ANTON PRIER, CHARLES DOHERTY, and PIERCE E. EVERETT, citizens of the United States, residing at 5 Kansas City, in the county of Jackson and State of Missouri, have invented a new and useful Improvement in Self-Closing Faucets, of which the following is a specification.

This invention pertains to an improved automatically-closing faucet; and it consists of a valve and its stem, said stem passing through the apertured seat of an elastic cushion or spring fitted upon and supporting the upper end of said valve-stem and a lever resting upon 10 said end of the valve-stem, substantially as hereinafter more fully set forth.

In the accompanying drawing the figure is a sectional elevation of our improved automatically-closing faucet.

20 In carrying out our invention we employ the faucet spout or nozzle A and the upright pipe A', with which the spout or nozzle is cast or connected, so that the lower surface of the inner end of the spout will form the top of the 25 pipe, the bottom surface of the interior of the spout or nozzle being inclined downward from its extreme inner end around the valve seat or opening therein toward its outer end. The purpose of this construction is to prevent the 30 water standing around the valve seat or opening and freezing thereat in cold weather.

B is the valve-stem, and B' its valve, the latter being conoidal in form, with its tapering surface projecting upward into and fitting 35 within the opening in the top of the pipe A, formed, as already stated, by the lower inner surface of the spout A, the sides of said opening being coincidentally inclined to form a seat, as at a, for the valve. The valve 40 is fitted upon a reduction of the stem, with its upper end resting against the shoulder thus formed on the stem, said valve being secured to the stem by a nut, b. The valve-stem B passes up through a water-tight aperture in a 45 partition or seat, C, formed or cast with the inner upturned portion, A², of the spout or nozzle A in the same vertical plane with the valve-seat opening a. The seat or partition C is preferably concaved, and has an air-aper- 50 ture, c, through it.

D is an elastic inverted cup-shaped cushion or spring, with its flared lower surface resting on the upper outer surface of the partition or seat C, forming an air-chamber, D', between said cushion and partition, while through the 55 upper surface of the cushion passes the upper end of the valve-stem B, to which it is connected by a shoulder, d, on the stem, arranged to fit against the under side of the cushion, and a pin, d', passed through an aperture in 60 the valve-stem, between the projecting ends of which pin and the cushion or spring is interposed a washer or disk, e.

E is an annular packing or ring, fitted with 65 in an externally-screw-threaded neck, f, formed upon the upturned portion A² of spout A, said packing or ring bearing upon the flared or flanged edge of the spring or cushion. The packing or ring E is itself secured in place by means of the cap F, provided with an internally-screw-threaded flange, which screws upon the externally-screw-threaded neck f of the spout A, said cap also having a shoulder, g, upon its inner surface, fitting upon the upper 70 surface of the packing or ring.

G is the valve-operating lever, pivoted to the 75 inside of the cap F and adapted to bear or rest upon the extreme upper end of the valve-stem B, and to extend through a vertical slot, h, in the cap a suitable distance beyond the cap to 80 be conveniently grasped and operated.

It will be noticed that when the lever is 85 moved so as to cause it to force the valve-stem, with its valve, downward, causing the valve to leave its seat, which will of course allow the water to pass from the pipe A' and be discharged, the cushion or spring D will yield or be compressed, and that when the lever is released the distending or expansive action of the spring or cushion D will cause the lifting 90 of the valve and its stem, and thus automatically stop the flow of water, while simultaneously the suction action produced by the in-rushing of air through the aperture c into the chamber D' beneath the cushion or spring D 95 will prevent the valve having a hammering action upon its seat.

Having thus fully described our invention, we claim and desire to secure by Letters Patent—

1. In a faucet, the pipe A', provided with 100

the nozzle or spout A at its top end, said spout having its bottom surface inclined outward around the communicating opening between it and the pipe, substantially as and for the 5 purpose set forth.

2. In a faucet, the combination, with the nozzled or apertured pipe and the valve and its stem, of the partition C, having an aperture, c, the elastic inverted-cup-shaped cushion or spring, and the valve-operating lever resting upon the valve-stem, substantially as and for the purpose set forth.

3. In a faucet, the combination of the pipe A', having the spout or nozzle A, provided

with the valve opening or seat, a screw-threaded neck, f, and apertured partition C, with the valve and its stem B, having a shoulder, d, plate e, and pin d', the elastic inverted-cup-shaped cushion or spring D, packing-ring E, screw-threaded cap F, and the lever G, substantially as and for the purpose specified.

ANTON PRIER.
CHARLES DOHEERTY.
PIERCE E. EVERETT.
